UNITED STATES PATENT OFFICE.

WILLIAM BORER, OF EVANSVILLE, INDIANA.

WRENCH.

1,164,164.

Specification of Letters Patent. Patented Dec. 14, 1915.

Application filed March 1, 1915. Serial No. 11,306.

To all whom it may concern:

Be it known that I, WILLIAM BORER, a citizen of the United States, residing at Evansville, in the county of Vanderburgh and State of Indiana, have invented certain new and useful Improvements in Wrenches, of which the following is a specification, reference being had to the accompanying drawings.

10 My present invention relates to new and useful improvements in wrenches and its principal object aims to provide a novel and peculiarly efficient form of locking device for holding the movable jaw of the wrench in adjusted position.

15 A more specific object of the invention is to so form the locking device that it may be easily released from engagement with the shank of the wrench to permit of free adjustment of the movable jaw, but will be automatically urged into locking engagement with the shank upon the slightest movement of the movable jaw away from the fixed jaw, when the wrench is in use.

20 The above and other additional objects are accomplished by such means as are illustrated in the accompanying drawings, described in the following specification, and then more particularly pointed out in the 25 claim which is appended hereto and forms a part of this application.

With reference to the drawings, wherein there has been illustrated the preferred embodiment of this invention as it is reduced 30 to practice, and throughout the several views of which similar reference numerals designate corresponding parts, Figure 1 is a top view. Fig. 2 is a face view of the wrench with a portion of the movable jaw broken 35 away. Fig. 3 is a bottom view; and Fig. 4 is a detail face view of the head of the wrench, showing particularly the movable jaw, the fixed jaw, and the locking device employed in connection with the movable 40 jaw.

45 As disclosed in the accompanying drawings, my wrench preferably consists in a shank or handle 10, a fixed jaw 11, which is formed integrally therewith, a movable jaw 12 which is slidable on the shank 10, a locking cam 13, and a yoke 14 which is slidable on the shank and is employed in normally maintaining the locking cam in operative 50 position.

55 The shank 10 and fixed jaw 11 are preferably formed in the nature of a steel casting,

although they may be made of any other desired metal and by any other preferred method.

The movable jaw 12 includes the jaw body 60 14' which is serrated on one face, as at 15 to provide a gripping surface co-acting with the serrated gripping surface 16 of the fixed jaw.

A sleeve 17 is formed on one longitudinal 65 edge of the movable jaw and is disposed for sliding movement over the shank 10. The channel defined by this sleeve is of such dimensions that the walls of the sleeve will snugly engage against the side faces of the 70 shank. The side walls of the sleeve, however, are spaced a greater distance than the width of the shank so that a small space indicated at 18 is provided to permit the transverse sliding movement of this sleeve 75 on the shank when it is desired to disengage the cam locking member from the shank.

The locking member 13 is pivoted at its outer terminal on a pin 19 which extends transversely between the spaced parallel 80 ears 20 formed on the terminal of the body of the movable jaw. The outer or free end portion of the cam 13 is enlarged transversely and is formed with an arcuate cam face or edge indicated at 21. Through this 85 enlarged portion extends a pivot pin 22 which is received by the free ends of the U-shaped yoke 14. This yoke 14 is slidable on the shank 10 and serves to hold the active end of the cam in operative position with 90 respect to the shank 10. The pivot pin 22 is located a less distance from the end 23 of the cam surface than from the other end 24 thereof. Thus, it will be seen that if the pivot pin 19 is moved toward the shank 10, 95 the cam will be swung on the pivot or axle 22 so as to release the cam from its engagement with the shank 10. In this connection it is to be observed that the pivot pin 22 is spaced from the adjacent face of the shank 10, a distance slightly less than the distance 100 between the point 24 and the pivot pin 22. It will be obvious that the pivot pin 19 may be moved toward the shank 10 by moving the fixed jaw transversely with respect to 105 the shank. This transverse movement of the movable jaw is provided for, of course, as hereinbefore explained by the space 18.

From the foregoing description, the operation of the locking member when the 110 wrench is in use will now be apparent. It will be seen that the movable jaw may be

adjusted toward the fixed jaw, without causing the binding engagement of the cam against the shank. When the wrench is applied to an article and pressure exerted thereon, the slightest movement of the pivoted jaw away from the fixed jaw will cause the cam to swing on the pivot pin 22 with a resultant forcing of the terminal portion 24 of the cam surface against the shank. Thus the movable jaw is held against movement away from the fixed jaw when the wrench is in use. When it is desired to release the cam, it is only necessary to place a finger against the outer edge of the movable jaw and slide the same toward the shank of the wrench with a resultant swinging of the cam 13 in the manner hereinbefore described.

In reduction to practice, it has been found that the form of this invention illustrated in the drawings, and referred to in the above description as the preferred embodiment is the most efficient and practical, yet realizing that the conditions concurrent with the adoption of this device will necessarily vary, it is desirable to emphasize the fact that various minor changes in details of construc-

tion, proportion and arrangement of parts may be resorted to, when required, without sacrificing any of the advantages of this invention, as defined by the appended claim.

What is claimed is:—

A wrench of the character described including a shank, a fixed jaw, a movable jaw, a sleeve formed on the movable jaw, said sleeve being slideable longitudinally and laterally on the shank, a pair of spaced parallel ears extending from the terminal of the movable jaw, a locking cam having its one terminal disposed between the ears, a pivot pin passing through the ears and cam, a substantially U-shaped yoke embracing the shank, said yoke being slideable thereon, and a pivot pin extending between the free ends of the yoke, said pivot pin passing through the cam, whereby the transverse sliding of the sleeve on the shank will cause the swinging movement of the cam on said pivot pin.

In testimony whereof I hereunto affix my signature in the presence of two witnesses.

WILLIAM BORER.
